UNITED STATES PATENT OFFICE.

WILLIAM M. BARKER, OF CANTON, OHIO.

CENTRIFUGAL FAN SEPARATOR.

Application filed February 24, 1925. Serial No. 11,302.

The invention relates to centrifugal fans used for exhausting or conveying pulverized material from a grinding mill or other source of supply; and the object of the improvement is to utilize the action of the fan for separating the material into different degrees of fineness as well as for impelling the same.

In the operation of a centrifugal fan for impelling pulverized material suspended in the air, it has been found that the centrifugal action of the fan wheel throws the larger particles of the material outward against the peripheral wall of the casing, while the smaller particles are not thrown outward as far, so that there is a segregation of different grades of fineness of the material in spiral zones, before the same is discharged through the outlet mouth of the casing.

The present invention involves the division of the discharge way in the throat of the outlet mouth of the fan casing, into two separate unobstructed air-way delivery channels, the one leading tangentially from the outer or peripheral portion of the outlet, and the other leading tangentially from an intermediate or inner portion thereof; so that the coarser material which is segregated to 30 and discharged from the outer portion of the outlet will flow through the one air-way channel, and the finer material which is discharged from an inner portion of the outlet will flow through the other air-way channel.

At the point of division it is preferred to provide an adjustable dividing or splitting blade in the throat of the outlet mouth, transversely fulcrumed at its rear edge at the junction of the adjacent walls of the 40 channels, and thence tapered forward to its free edge, so that the same may be swung outward and inward toward and from the peripheral wall of the casing at the outlet thereof, for dividing the material flowing through the outlet according to the different spiral zones into which the same has been segregated.

The centrifugal fan separator may be used in any position where it is desired to 50 impel pulverized material without regard to the direction into which the delivery is made, for the reason the separation is effected by the action of centrifugal force as distinguished from the action of gravity; and the 55 unobstructed air-way delivery channels leading from the fan separator can be di-

rected upward or downward or laterally either way from the top or bottom of a fan operating on a horizontal axis, or may lead from any point in the periphery of a fan operating on a vertical or inclined axis.

Furthermore, the fan separator can be combined directly with grinding apparatus, such for instance as a grinding or pulverizing mill, and when so combined the unobstructed air-way delivery channel carrying the coarser material can lead to a hopper or other means for feeding back into the mill for regrinding while the unobstructed air-way delivery channel carrying finer material, 70 can lead to a hopper or other means for storage or disposal.

Such an embodiment of the invention is illustrated, without being limited thereto, in the accompanying drawings, forming part 75 hereof, in which—

Figure 1 is a sectional view, normal to the axis of the centrifugal fan separator;

Fig. 2, a side elevation of the same combined with a ball mill; and

Fig. 3, an edge elevation of the same.

Similar numerals refer to similar parts throughout the drawings.

A centrifugal fan wheel 4 is mounted in a spiral casing 5 so as to form a peripheral 85 channel 6 gradually increasing in radial depth to the outlet opening 7 of the casing.

The throat of the discharge way 8 leading from the outlet mouth 7 is formed by a tubular wall extension from the peripheral 90 wall of the casing, the outer extension being substantially tangential to the peripheral wall of the casing, and the throat of the discharge way is divided into two unobstructed air-way delivery channels 8' and 8'' by suitable walls 9' and 9'' interposed between the extension walls 9.

A dividing blade 10 is preferably provided across the throat of the discharge way 8, one edge of which is fulcrumed at 10' at 100 the junction of the dividing walls of the delivery channels, and the other free edge 10'' is located in the mouth of the outlet opening of the fan casing parallel with the axis of the fan, so as to divide the material 105 laden air as it flows outward through the throat of the same.

A suitable crank arm 11 is connected with the fulcrum of the dividing blade external to the casing, for adjusting the same in various positions; and suitable means as a spring detent 12 and a cooperating segment

13, may be used for holding the blade in a given position of adjustment.

When the fan wheel is operated to impel pulverized material through the fan casing, its centrifugal action throws the air carrying the coarser material outward into a spiral zone flowing around and along the peripheral wall of the casing, while the air carrying the finer particles of material are thrown outward a lesser distance, so as to form a spiral zone along the periphery of the wheel, as illustrated in the drawings; and as the material laden air, thus segregated into spiral zones of differential sizes, flows through the outlet opening of the casings, it is divided and directed into the respective unobstructed air-way delivery channels by which the different size material and the air carrying the same are conducted away from the fan separator.

A suitable adjustment of the dividing blade serves to control the difference in the size of the material which is conducted by the air current into and through the respective delivery channels; and in this manner, a separation of the coarser from the finer particles of the pulverized material flowing with the air currents, is effected directly by the action of the fan and the dividing blade located in the throat of the outlet mouth thereof.

As shown in Figs. 2 and 3 the fan separator 5^a may be mounted to receive pulverized material directly from a ball mill 14, and in this use of the apparatus the unobstructed delivery pipe 8^{a'} for the air current carrying the coarser material may discharge into a hopper 15 leading into the feed pipe 16 of the ball mill for regrinding the coarser material; and the unobstructed delivery pipe 8^{a''} for the air current which

carries the finer material, may discharge the same into a hopper 17 for storage or other disposition.

I claim:—

1. A fan separator including a centrifugal wheel, a spiral casing for the wheel receiving pulverized material and having an outlet mouth and a discharge throat attached to and leading tangentially therefrom, and a blade in and carried by the walls of the discharge throat and parallel with the axis of the fan dividing the discharge throat into a plurality of separate unobstructed air-way delivery channels for the flowing air which carries different size material through the respective channels. 45 50 55

2. A fan separator including a centrifugal wheel, a spiral casing for the wheel receiving pulverized material having an outlet mouth and a discharge throat attached to and leading tangentially therefrom, and a blade in and carried by the walls of the discharge throat and parallel with the axis of the fan dividing the discharge throat into outer and inner unobstructed delivery channels for the flowing air which carries different size material through the respective channels. 60 65

3. A fan separator including a centrifugal wheel, a spiral casing for the wheel receiving pulverized material having an outlet mouth and a discharge throat leading tangentially therefrom, and an adjustable blade in the discharge throat dividing the discharge throat into a plurality of separate unobstructed air-way delivery channels for the flowing air which carries different size material through the respective channels. 70 75

In testimony that I claim the above, I have hereunto subscribed my name.

WILLIAM M. BARKER.
